(57) **CLAIM**

The ornamental design for a tibial impaction tool, as shown and described.

DESCRIPTION

FIG. 1 is a perspective view of a tibial impaction tool shown in an environment illustrating our new design;

FIG. 2 is a top plan view of the tibial impaction tool shown removed from its environment in order to show aspects of the design that are not apparent in the perspective view;

FIG. 3 is a bottom plan view thereof;

FIG. 4 is a left side elevation view thereof;

FIG. 5 is a right side elevation view thereof;

FIG. 6 is a rear end elevation view thereof; and,

FIG. 7 is a front end elevation view thereof.

The broken lines shown that are immediately adjacent the shaded areas represent unclaimed boundaries while all other broken lines are directed to environment and are for illustrative purposes only; the broken lines form no part of the claimed design.
